Primary Examiner — Catherine R Oliver-Garcia

(21) Appl. No.: **29/675,903**

(74) *Attorney, Agent, or Firm* — Holland & Hart LLP

(22) Filed: **Jan. 7, 2019**

CLAIM

(51) LOC (13) Cl. **14-03**

The ornamental design for a grip and stand accessory for a personal electronic device, as shown and described.

(52) U.S. Cl.

DESCRIPTION

(58) **Field of Classification Search**

USPC ..... D3/218; D14/140, 142, 148–149, 217, FIG. 1 is a perspective view showing a new design for a grip and stand accessory for a personal electronic device;

D14/250–253, 451–452, 440, 434, 447, FIG. 2 is a front view of FIG. 1;

USPC **D14/251**; D3/218

FIG. 3 is a rear view of FIG. 1;

USPC ..... D3/218; D14/140, 142, 148–149, 217, FIG. 4 is a left-side view of FIG. 1;

D14/250–253, 451–452, 440, 434, 447, FIG. 5 is a right-side view of FIG. 1;

USPC **D14/251**; D3/218

FIG. 6 is a top view of FIG. 1;

CPC ..... A45C 2200/15; A45F 5/10; F16M 11/10; FIG. 7 is a bottom view of FIG. 1;

F16M 11/40; F16M 11/105; F16M 13/00;

G06F 1/1626; G06F 2200/1633; H04M

1/04; H04M 1/6075; H04M 1/72569;

H04M 1/72577; H04M 17/026; H04M

1/006; H04M 1/0214; H04M 1/0233;

H04M 1/0254; H04M 1/0264; H04M

1/0279; H04M 1/18; H04M 1/6091;

H04M 1/723; H04M 1/725; H04M

2207/206; H04M 2250/16

See application file for complete search history.

FIG. 8 is a perspective view showing a first alternative new design for a grip and stand accessory for a personal electronic device;

FIG. 9 is a front view of FIG. 8;

FIG. 10 is a rear view of FIG. 8;

FIG. 11 is a left-side view of FIG. 8;

FIG. 12 is a right-side view of FIG. 8;

FIG. 13 is a top view of FIG. 8; and,

FIG. 14 is a bottom view of FIG. 8.

The broken lines showing portions of the grip and stand accessory for a personal electronic device are included for the purpose of illustrating environment and form no part of the claimed design.
